UNITED STATES PATENT OFFICE.

FRED M. GORDON, OF DETROIT, MICHIGAN.

RAZOR-SHARPENING MACHINE.

1,085,602.

Specification of Letters Patent.

Patented Feb. 3, 1914.

Application filed November 15, 1912. Serial No. 731,463.

To all whom it may concern:

Be it known that I, FRED M. GORDON, a citizen of the United States, residing at Detroit, in the county of Wayne and State 5 of Michigan, have invented certain new and useful Improvements in Razor-Sharpening Machines, of which the following is a specification.

This invention relates to machines for 10 sharpening razors, and more especially to that class thereof adapted to receive the blades of safety razors, and it has for one of its objects the provision of improved means whereby the blades will be carried 15 into contact with the sharpening device so as to have a yielding movement and pressure exerted upon the mechanism which controls the movement of the blade relatively to the sharpening media.

20 The invention has, furthermore, for its object the provision of a two-part mechanism whereby the blade holder is controlled, one part remaining in fixed position relatively to the operating member, while the 25 other part is movable and adapted to be connected with and disconnected from the first member.

The invention has, furthermore, for its 30 object the combination with the sharpening device and the driving mechanism thereof, of means whereby the sharpening devices can be driven only in the proper direction, so that consequently all danger of cutting the sharpening devices through accidental 35 retrograde movement thereof will be obviated.

Further objects of the invention will hereinafter appear and be particularly defined in the claims.

40 The invention has been clearly illustrated in the accompanying drawings in which similar characters denote similar parts, and in which—

Figure 1 is a top view of a razor-sharpening machine embodying my invention. Fig. 2 is a side view of one of the blade holders and its operator. Fig. 3 is an end view thereof. Fig. 4 is a section on line 4, 45 of Fig. 2. Fig. 5 is a central vertical section of the machine. Fig. 6 is an inner end view of the blade holder, in opened condition. Fig. 7 is a view similar to Fig. 6 showing the blade holder closed.

Briefly stated, the present machine comprises a pair of spaced sharpening disks between which the blade holder plays to bring the opposite faces of the razor edge into engagement therewith, alternately. The several blade holders are mounted on a table which can be turned around by the operator 55 to bring any one of the holders in front of him for the purpose of replacing a sharpened blade by a dull one. The table carries a motor which through intervening mechanism is connected for driving the 60 sharpening disks and also for operating the razor blade holders at different rates of speed required by the work to be done.

Referring to the drawings, 10 denotes a pedestal or post which is tubular to permit 70 the passage of a pair of electric conductors 11, 12 which may be connected at their lower ends by a switch 13, and which terminate at their upper ends in a central plate 14 and an annular contact plate 15, respectively, 75 both plates being insulated from each other on a collar 16 fixed on the upper end of the pedestal. Loosely mounted on the reduced portion 10' of the pedestal is the hub 17 of a spider which supports a table 18 upon 80 which the several active elements of the machine are carried. These include a motor M to which electric power is furnished by conductors 20, 21 which are connected with the plates 14 and 15 by resilient contact brushes 85 22, 23 respectively, so that in this manner electric power will be imparted to the motor, no matter which position the table may occupy.

Secured to the underside of table is a casing C in which is journaled a shaft 25, having a worm 26 in engagement with a worm gear 27 secured upon a shaft 28 in any suitable manner, as for instance through the intervention of the hub 29' of a gear 29 which 95 is fixed upon the shaft 28 and carries at its upper end a pinion 30. The gear 29 drives a pinion 31 which is firmly secured to an arbor 32 journaled in suitable bearings in the casing and table and having at its upper 100 end a pair of disks S S' which are spaced apart and have annular sharpening members s, s' respectively. The pinion 30 above referred to is in engagement with a gear 35 which is attached to a sleeve 36 loose 105 upon the shaft 32 and carrying at its upper

end a cam 37 whereby the blade holders are operated to bring the opposite sides of the razor blades alternately into contact with the sharpening members.

5 From the foregoing it will be understood that when the spindle 28 is rotated, the sharpening members will be driven at a greater rate of speed than the cam.

Means are provided whereby the motor M 10 can drive the shaft 25 only in the right direction, a feature which is important for the reason that, if the sharpening members S, S' should be accidentally driven in a reverse direction, while razor blades are in 15 contact therewith, the latter would dig into the sharpening material which preferably consists of leather belting or the like. The means above referred to comprise a pulley 40 loose upon the shaft 25 and carrying a 20 spring-actuated pawl 41 normally in engagement with a tooth 42 provided on a disk 43 which is tightly secured to the shaft 25, the pulley P of the motor being connected by a belt b with the pulley 40, the proper 25 rotation of which is indicated by arrow a, in Fig. 5. It will therefore be evident that if for some reason the movement of the motor be reversed, or the belt between motor and pulley 40 should not be of the proper 30 kind, or crossed, the pulley would simply run idle without imparting motion to the shaft 25.

The construction of the blade holders, together with their operating mechanism is 35 clearly shown in Figs. 2, 3, 6, and 7 and in the present instance I employ a series of these devices, the holders being adapted to be shifted on the table, radially thereof, as shown in Fig. 1. The holder proper 40 comprises a pair of jaws 50, 51 (see Figs. 6 and 7), the former of which forms an integral part of a tubular spindle pivot 52 which is journaled in a bearing 53 of the holder bracket 54 (see Fig. 2). At its other end 45 the spindle pivot carries an arm 55 which is slotted, as at 56, to receive a pin 57 carried by the free end of a resilient crank arm 58, shown therein as a blade spring, and having its lower end rigidly attached to the outer 50 end of a rock spindle 59 which is also journaled in the bracket 54. This bracket has also a pair of spaced lugs 60 whereby the bracket in its entirety may be moved along 55 on guide rods 61, the outer ends of which are fixed in a bracket 62, and the inner ends 60 of which are supported by a bracket 63, both brackets being secured to the top of the table 18. When the bracket 54 has been moved outwardly until it nearly approaches the bracket 62, both jaws 50 and 51 of the 65 blade holder will be clear of the sharpening disks, as is clearly shown at H in Fig. 1. On the other hand, when the bracket 54 is slid inwardly until it approaches the bracket

53, the blade will be in position between the 65 sharpening disks and at the same time the rock spindle 59 will be brought into contact with an actuator having a fixed location on the table and comprising a rock shaft 64 which is journaled in the bracket 63 and has 70 in its face a slot 65 adapted to receive a pin 66 projecting from the rock spindle 59, so that in this manner the rock-spindle and rock shaft will always be caused to be connected in the same position relatively to each other. 75 Oscillatory movement is imparted to the rock shaft 64 by a lever 65' secured to the inner end thereof and being bifurcated to receive antifriction rollers 67, 67' in engagement with the upper and lower faces of the 80 cam 37 above referred to, so that the position of the rock shaft is at all times under direct control of said cam.

By referring to Fig. 6 it will be noted that the two jaws 50, 51 are normally separated or opened by a spring 70 surrounding a holding stud 71 whereby said opening movement is limited. The jaws are closed by a cam projection 72 provided on the end of a rod 73 which extends through the spindle 90 52 and has at its outer end a finger button 74 whereby it may be turned as shown in Figs. 6 and 7.

From the foregoing it will be understood that the oscillation of the rock-spindle 59 95 will swing the arm 55 of the holder spindle to an amount more than necessary to bring the blade into contact with the sharpening disks respectively. By virtue of making the pin 57 adjustable on the spring 58, the pressure under which the blade in the holder is presented to the sharpening disks, may be varied as desired.

In some instances it may be necessary to 100 grind a blade before it is subjected to the operation of the sharpening disks, and for that reason I have provided a grinding wheel G which is secured to the spindle 32, ready of access to the operator.

Many changes may be made in the general organization as well as in the particular construction of some of the component elements of my improved machine, without departing from the spirit of the invention, especially in the mechanism for safeguarding 11 against the retrograde movement of the sharpening disks relatively to the blade holders.

I claim:

1. In a razor sharpening machine, the 12 combination with a pair of spaced sharpening disks, and means for rotating the same, a table, a blade holder shiftable on the table, an actuator for said holder having a fixed 13 position on the table, means for cooperatively connecting said actuator and blade holder when the latter is in its inward position, and means for operating said actuator.

2. In a razor sharpening machine, the combination with a pair of spaced sharpening disks, and means for operating the same, of a table, a blade holder shiftable radially on the table and comprising a rock spindle, an actuator for said holder having a fixed position on the table and comprising a rock shaft, means for coöperatively connecting said rock-spindle and rock shaft when the 10 blade holder is in its inward position, and means for operating said rock shaft.

3. In a razor sharpening machine, the combination with a pair of spaced sharpening disks, and means for operating the same, 15 of a table, a blade holder comprising a rock spindle, guide rods for shiftably supporting said blade holder on the table, a rock shaft journaled in a bearing stationary on the table, means for operating said rock shaft continuously 20 during the operation of said disks, and means for coöperatively connecting said rock-spindle and rock shaft when the former is in its inward position.

4. In a razor sharpening machine, the combination with a pair of spaced sharpening disks, and means for operating the same, 25 of a table, a blade holder adapted to be shifted into and out of position between said disks, said blade holder comprising a pair of jaws and a rock spindle therefor, resilient means connecting said rock spindle and jaws, an actuator for said holder having a fixed position on the table and comprising a rock shaft, and means for coöperatively 30 connecting said rock-spindle and rock shaft when the blade holder is in its inward position.

5. In a razor sharpening machine, the combination with a pair of spaced sharpening disks, and means for operating the same, 40 of a table, a blade holder shiftable on the table, an actuator for said holder having a fixed position on the table, and adjustable means for coöperatively connecting said holder and actuator for varying the amount 45 of rocking movement of said holder between said disks, and means for operating said actuator.

6. In a razor sharpening machine, the combination with a pair of spaced sharpening disks, and means for operating the same, 50 of a table, a blade holder shiftable on the table and comprising a rock spindle, an actuator for said holder having a fixed position on the table and comprising a rock shaft, and a pin-and-slot connection between 55 said rock spindle and rock shaft and adapted to be placed into engagement when the holder is in its inward position.

60 7. In a razor sharpening machine, the combination with a pair of spaced sharpening disks, and means for operating the same, of a table, a blade holder comprising a bracket, a pivot-spindle journaled therein

and having a lever, a rock spindle having a 65 resilient arm connected with said lever, an actuator for said holder having a fixed position on the table and comprising a rock shaft, and means for cooperatively connecting said rock shaft and said rock spindle 70 when the holder is in its inward position.

8. In a razor sharpening machine, the combination with a pair of spaced sharpening disks, and means for operating the same, 75 of a table, a blade holder radially movable thereon, an actuator for rocking said blade holder, a rotatable cam for actuating said actuator, and a slip connection between said holder and actuator for connecting the same when the holder is in its inward position, 80 and for disconnecting the same when the holder is in its outward position.

9. In a razor sharpening machine, the combination with a pair of spaced sharpening disks and means for operating the same, 85 of a table, a blade holder comprising a bracket slidably supported on the table, a pivot-spindle journaled in said bracket, a slotted lever carried by said pivot-spindle, a rock spindle journaled in said bracket and 90 having an arm, resilient means for connecting said arm and lever, an actuator comprising a rock shaft journaled in a bearing stationary on a table, and a slip connection between said rock spindle and rock shaft 95 for connecting these elements when the holder is in its inward position, and for releasing said rock spindle when the holder is in its outward position.

10. A razor blade holder comprising a 100 bracket, a pivot-spindle journaled therein, a pair of jaws at one end of said spindle, a slotted lever on the other end thereof, a rock spindle journaled in said bracket substantially in parallelism with and remote 105 from said pivot-spindle, a blade spring carried by said rock spindle, a pin adjustably carried by said blade spring and engaging said slot, and means for positively moving said rock spindle.

11. A razor blade holder comprising a bracket, a pivot-spindle journaled therein, a pair of jaws at one end of said spindle, a slotted lever on the other end thereof, a rock spindle journaled in said bracket substantially in parallelism with and remote 115 from said pivot-spindle, a blade spring carried by said rock spindle, a pin adjustably carried by said blade spring and engaging said slot, a bifurcated lever connected with 120 said rock spindle, and a cam between the branches of said lever for positively moving the same.

12. A razor blade holder comprising a bracket, a pivot-spindle journaled therein, 125 a pair of jaws at one end of said spindle, a slotted lever on the other end thereof, a rock spindle journaled in said bracket sub-

stantially in parallelism with and remote from said pivot-spindle, a blade spring carried by said rock spindle, a pin adjustably carried by said blade spring and engaging said slot, a bifurcated lever having a pair of spaced studs, rollers journaled on said studs, a cam traveling between said rollers, and means for connecting said lever with said

rock spindle in certain predetermined positions relatively to each other.

In testimony whereof I affix my signature in presence of two witnesses.

FRED M. GORDON.
